FIG. 5.

UNITED STATES PATENT OFFICE

2,360,741

WIRE DISTRIBUTOR FOR WIRE-DRAWING MACHINES

Daniel D. Symmes, West Haven, Conn., assignor to The American Steel and Wire Company of New Jersey, a corporation of New Jersey

Application October 1, 1941, Serial No. 413,221

8 Claims. (Cl. 205—16)

This invention provides certain improvements in the production of wire, the character of which improvements will become apparent hereinafter.

In accordance with the usual wire-drawing practice, it is customary to place the bundles of wire to be drawn onto a revolving device commonly called a "swift," which consists of a spoked, tapered rack which is free to revolve on a simple spindle. One end of the wire is passed through the die to the block, which is power-driven and rotates so as to pull the wire from the swift and through the die. In the event of high-speed blocks, the rotation of the swift is rapid, whence the name.

In such practice, there is provided no control on the wire, as the wire-drawing machines usually are single-draft machines, that is, a separate swift for each block, and the machine speeds formerly were not very high.

The single draft machines formerly employed have been superseded largely, if not entirely, by high-speed, multiple draft, continuously operating machines. With the advent of these machines, it becomes apparent that absolute control of the wire from the swift to the machine would be very desirable. The present invention provides such control. Obviously, machines that are running are the productive machines, and the less shut-downs, the greater the productivity. Also, ease of operation enhances efficiency of labor.

In operating such machines, whether they be the single draft type, or the high-speed, multiple draft, continuous wire-drawing machines, defects in the wire being processed are encountered inevitably, and wholly without regard to the machine.

Thus, the bundles of wire often have "kinks" therein; the wire becomes snarled; it may accumulate "lumps" of lead from heat treating furnaces; and also the wire is liable to an excess of lime from cleaning.

From these defects, various difficulties and malfunctions are encountered during the drawing operation. A kink in the wire or a lump of lead thereon will break the wire immediately upon reaching the die. Snarled wires cause the swifts to be drawn along the floor to the wire-drawing machine, breaking the wire. Also, when a swift has been emptied, the machine is down until another bundle is positioned and the ends of the wire are welded together.

In the event of a wire break on a high-speed continuous wire-drawing machine for fine sizes, there is the resulting necessity that from ten to

twelve drawing dies must be restrung, which requires an average time of from twenty to thirty minutes to accomplish. For preventing this, operators customarily allow the wire to pass 5 through their closed hand, hoping thereby to detect kinks and lumps. Also, while doing this, an operator must be on the alert in the event of a swift "walking" up to the machine; and when an operator is tending more than one machine, a great amount of time is consumed by his having to be very careful to place the coils of wire to be drawn nicely upon the swifts.

As has been indicated above herein, one of the objects of the present invention is to provide an 15 absolutely automatic control for the wire during the entire drawing operation, which will eliminate the difficulties indicated above; which minimizes shut-downs; and increases the ease of operation.

20 Further objects of the invention will become apparent as the description proceeds, and the features of novelty will be pointed out in particularity in the appended claims; and it will be understood that the adaptation of the invention 25 as shown in the accompanying drawings is intended to be illustrative only of an application of the invention, which invention is intended to embrace within its scope such modifications, changes, and re-arrangement of parts as may 30 become necessary to adapt it to varying conditions and uses as may be commensurate with the scope of the appended claims.

The invention will be understood more readily by reference to the accompanying drawings, in 35 which

Figure 1 represents a plan view of a wire-drawing machine to which the improvements of the present invention are applied;

40 Figure 2 is a side elevation of the machine of Figure 1;

Figure 3 is a fragmentary sectional view of a part of the apparatus, the view being indicated along the line III—III of Figure 2;

45 Figure 4 is an enlarged fragmentary elevation taken generally along the line IV—IV of Figure 2, looking in the direction of the arrows; and

Figure 5 is a detail wiring diagram of the control of the present invention.

50 It will be understood that the automatic control now to be described is adapted to be applied to any wire-drawing machine, although it is of particular value as applied to high-speed continuous machines, referred to previously herein.

55 Referring more particularly to the drawings, A

designates a wire-drawing machine of any suitable type, which is driven by a motor B.

Associated with the machine A are similar non-rotating carrier frames 1, 1', each of which is adapted to receive several bundles of wire 9, the ends of which are welded together to make a continuous bundle. Each of the carrier frames has mounted thereon a feed arm 11 which rotates on a spindle 13 secured in the top of the carrier frame. The arm 11 is held on the spindle 13 by a tension member 15, which is adjustable by a thumb-screw 17. Each of the arms 11 is provided with springs 19 on its outer end, which springs define a slot 21 between them. This slot is adapted to receive the free end of the wire 23 unwound from the bundle 9.

Positioned adjacent the carrier frames is an upright standard 25, which is mounted on a suitable base 27. This standard 25 is provided at its bottom with a sleeve 29, which is slidable vertically on the standard. The sleeve 29 carries a bracket 31 in which is mounted turnably a pulley sheave 33, which turns on the shaft 34. The top of the standard 25 is outset, as shown at 35, a sleeve 37 being mounted on this enlarged portion 35.

The sleeve 37 carries an outwardly projecting arm 39 which carries a pulley-sheave 41 which is turnable on its shaft 43. At the end of the arm 39 there is provided an off-set bracket 45 in which is mounted a guide bushing 47. This bushing normally allows the wire to freely pass through it, the passage for the wire being not much larger than the wire. But if abnormal conditions are present on the wire surface, such as kinks in the wire or lumps of coating material on the surface of the wire, engagement thereof with the bushing stops the wire and brings into play the control mechanism, as will be described hereinafter. The sleeve 37 also carries a sheave 49 which is turnable on its shaft 51 mounted in bracket 53. Another sheave 55 is mounted on brackets 57 on the standard 25, and turns on its shaft 59. On the base 27 there is mounted a box 61 which encloses a limit switch mechanism actuated by an actuator arm 63 having a contact roller 65 in engagement with the sleeve 29.

Wire 23 from the bundle is snapped between the spring 19 into the slot 21 of the feed arm 11. This arm is formed into a radius curve, which causes the arm to extend over the upper part of the frame 1. The feed arm 11, therefore, is a planetary arm which revolves around the frame 1 under the tension exerted by the machine A. The wire then is passed through guide bushing 47 and over the sheave 41, then under the sheave 33, through arm 39, over the sheave 49, and then under sheave 55, the wire then going into the wire-drawing machine.

At the exit end of the machine there is provided a free-running sheave 67 which is mounted on a lever 69, which lever is attached to the machine A, forming one side of the control circuit, to be referred to in greater detail hereinafter. The sheave 67 rests by its own weight on the drawn wire 23 as the wire emerges from the machine A and becomes wound on block 71, which is rotated by motor B. Below the lever 69 is a pin 73, which is insulated suitably from the machine A.

Now, while the machine A is operating and producing, the operator loads up the second carrier 1'. When the carrier 1' is loaded, the bottom end of the bundle 9 on carrier 1 is welded to the top end of bundle 9' on carrier 1', and the wire 23' from this bundle 9' is snapped through the

springs 19' (corresponding to spring 19) on feed arm 11' which corresponds to feed arm 11.

When all of the wire has been uncoiled from the carrier 1, and while the machine is still running, the wire 23 will snap out of slot 21 in feed arm 11 and the angular tension from the feed arm 11', or carrier 1' will cause the distributor arm 39 to swing over into the dotted line position over the carrier 1' and the drawing operation is continued. Meanwhile, carrier 1 is reloaded and the procedure goes on continuously.

It will be seen that since the distributor arm 39 can move into two positions, means must be provided to enable this action to occur. A convenient way to do this is to mount a cam 75 on the distributor standard or column 25, the mounting being made by any suitable means, such as screws 77 (Figure 4). The distributor sleeve 37 is provided with two cam notches, which are shown at 79 (Figure 4), which interlock with the cam 75, and which are positioned on the circumference of the sleeve 37 so as to assure proper angular adjustment of the distributor arm 39. Pull of the wire 23 on the arm effects the proper adjustment of the sleeve 37 relative to the cam 75.

This operation proceeds as long as the machine is running smoothly and no obstructing defects are encountered as the wire is pulled through the machine. But sooner or later some such defect will be encountered, which puts into operation the control mechanism of the present invention.

The details of this control are shown in Figure 5.

In Figure 5, the current supply line is indicated at 81, 83 and 85, which supplies current to the motor B of the machine A, which motor may be either a two-phase or a three-phase motor. The supply line is shown as being operable responsive to abnormal conditions in the wire 23, the supply line being provided with contacts 81a, 83a and 85a, which are adapted to engage contacts 81b, 83b and 85b in the main power line, designated 81c, 83c, and 85c; when the motor B of the machine A is operating, a relay 86 controls the contacts in the power line.

This relay comprises movable contacts 87 and 87a, which are adapted to engage fixed contacts 89 and 89a; these movable and fixed contacts being normally closed.

These contacts of the relay 86 are connected as follows:

The movable contacts are connected by a conductor 88 to a fixed contact 90 of an overload solenoid, the coil of which is indicated at 91 to be connected at both sides to the line conductor 85. Contact 90a of the overload solenoid is the movable contact and is connected to one side of a release coil 92 through conductor 93. The other side of the coil 92 is connected through lead 94 to the power line conductor 85c.

The fixed contacts 89 and 89a of the relay 86 are connected through suitable resistances 89b and 89c to a contact 95 by way of conductor 96. A spaced contact 97 is connected through conductor 98 to a contact 97a, this contact being, in turn, connected by conductor 98a to one side 97b of an interlocking switch 99.

The space between contacts 95 and 97 normally is closed by a suitable stop switch 100, which is illustrated as being a push-button which normally bridges the space between the contacts and connects them together.

An operating terminal 101 for the switch 99 is connected through lead 102 to the power line conductor 81c, and also by conductor 103 to a starting terminal 101a which is spaced from another

starting terminal 81a, this space being adapted to be closed by a starting switch 100a, which is conveniently a push-button and which normally is open.

Relay 86 is opened by a coil 104 becoming energized, which happens if anything occurs to wire 23 to lift the bracket 29 on the post 25 to cause limit switch 61 to close, or to cause the switch 69 on the machine A to drop to contact with pin 73, the coil 104 being in a low-voltage circuit which is closed when either of the foregoing normally open switches becomes closed.

Connected across the line conductors 81 and 83 is the high voltage side 106 of a step-down transformer 108. The low-voltage side 105 of the transformer 108 is connected on one side through conductor 109 to a contact 107 of limit switch 61 and also to contact 107a of switch 73. The other side of the low-voltage side 105 of the transformer is connected through a lead 111 to one terminal 110 of the coil 104. The other terminal 112 of the coil 104 is connected through conductor 114 to contact 114a of the limit switch 61 and to contact 115 of the switch 73 on the wire-drawing machine A.

When the transformer circuit is energized by abnormal conditions, in the wire 23, tension on the wire lifts bracket 31 and moves switch arm 63 until it closes contacts 107 and 114a, thereby closing the transformer circuit and energizing coil 104 which opens the relay contacts. Or if the wire 23 breaks to allow roller 67 to drop onto pin 73, such dropping closes contacts 107 and 115 to close the solenoid circuit and energize the coil 104.

To start the motor B of the machine A, push-button 100a is closed, which closes a circuit from power line conductor 81c, conductor 102 to terminal 101, through conductor 103, contact 101a, push-button 100a, contact 97a, contact 97, push-button 100, contact 95, conductor 96, relay 86 (the contacts of which normally remain closed) conductor 88, normally closed overload contacts 90 and 90a, conductor 93, through coil 92 which is energized, through conductor 94 to power line conductor 85c.

When the coil 92 is energized, contacts 81a, 85a, and 83a close with contacts 81b, 85b and 83b, respectively, the contacts being controlled by the coil 92. Closing of these power line contacts allows current to flow to motor B to run the motor.

Simultaneously with the closing of the power line contacts, interlocking switch 99 closes and holds as long as current flows through the power line. Therefore, button 100a may open when current will flow through interlocking switch 99, conductor 98a, through the relay 86 as before, thence, as before, through coil 92 to maintain this coil energized and the power line contacts close.

Now, when stop button 100 is opened, this circuit is broken and the coil 92 is deenergized and the power line contacts open. Or, if an overload occurs through the power line, overload coil 91, which is connected to power conductor 85, becomes energized to open the overload contacts 90 and 90a to deenergize the coil 92 and break the power circuit.

Or, if anything happens to the wire to cause switch 61 or pin 73 to be closed, current will flow through the transformer circuit to energize coil 104, which will open relay 86 and deenergize the coil 92, thereby opening the power line circuit and stopping the motor B.

With the apparatus described herein, enough

wire is contained on the two carriers 7 and 7' for twenty-four hours' operation. In a specific practice, the invention is applied to particular machines which are capable of taking twelve drafts each. One operator tends seven machines, having a total of eighty-four drafts. The distributor mechanism is positioned rigidly, close to the machine and there results a large increase in production over former procedures, and the simplicity and ease of loading materially improves the morale of the operator.

I claim:

1. Wire-drawing apparatus comprising, in combination, a wire-drawing machine, a plurality of wire-holding reels adjacent to the machine, the said reels being adapted to receive bundles of wire and to feed wire therefrom continuously to the wire-drawing machine, wire-distributing instrumentalities including a planetary unwinding arm mounted on each reel and a feeding arm intermediate the reels and machine, the said arm being mounted to shift automatically from one of the reels to another responsively to directional tension on the wire passing through the said arm, depending from which of the reels is being unwound, and adapted to supply continuously wire from the bundles to the wire-drawing machine, and mechanism for stopping the machine responsively to malfunctioning of the said wire-distributing instrumentalities or breaking of the wire.
2. Wire-drawing apparatus comprising, in combination, a wire-drawing machine including a plurality of wire-holding reels adapted to receive bundles of wire and to feed wire therefrom continuously to the wire-drawing machine, a power circuit for driving the machine, wire-distributing instrumentalities adapted to supply continuously wire from the bundles to the wire-drawing machine, the said instrumentalities including unwinding means for unwinding wire from the bundles, the unwinding means being shiftable between the reels responsively to unwinding of the wire therefrom, and control mechanism for stopping the wire-drawing machine responsively to malfunctioning of the said instrumentalities or breaking of the wire, the control mechanism including a control switch in the power circuit, a control circuit, means for energizing the control circuit responsively to the malfunctioning of the said instrumentalities or the breaking of the wire, and mechanism for opening the control switch responsively to the energizing of the control circuit, thereby instantaneously stopping the said machine.
3. Wire-drawing apparatus comprising, in combination, a wire-drawing machine, a plurality of wire-holding reels adjacent to the machine, the said reels being adapted to receive bundles of wire and to feed wire therefrom continuously to the wire-drawing machine, a planetary unwinding arm rotatably mounted on each of the reels for receiving wire from the reels and adapted to rotate around the reels to unwind the wire responsively to tension on the wire, a motor for driving the wire-drawing machine, a power circuit for supplying current to drive the motor, a control circuit for the motor, a relay normally closing the power circuit, guide means for the wire providing an obstruction to passage of the wire therethrough under action of abnormal surface conditions of the wire engaging the guide means, thereby producing abnormal tension on the wire incident to the stopping of the wire at the guide means and continued pull on the wire 70 by the wire-drawing machine, slack-forming

means between the guide means and the wire-drawing machine, the said slack-forming means being operable under action of the said abnormal tension of the wire, and means operable by the slack-forming means through abnormal tension on the wire to close the control circuit for opening the relay, thereby stopping the motor responsively to the wire being drawn becoming under abnormal tension.

4. Wire-drawing apparatus comprising, in combination, a wire-drawing machine, a plurality of wire-holding reels adapted to receive bundles of wire and feed wire therefrom continuously to the wire-drawing machine, mechanism for feeding wire uninterruptedly from the reels to the wire-drawing machine, the said mechanism including a guide bushing and slack-forming means, the guide bushing being adapted to normally pass the wire freely therethrough while stopping the wire under abnormal conditions of the surface thereof, a motor for operating the wire-drawing machine, a power circuit for supplying current to drive the motor, a control circuit for the motor, a relay normally closing the power circuit, and a limit switch adapted to be closed by the wire passing to the wire-drawing machine becoming subjected to predetermined abnormal tensions incident to engagement of abnormal surface conditions on the wire with the guide bushing, thereby stopping the wire, the closing of the limit switch energizing the control circuit for opening the relay, thereby breaking the power circuit and stopping the motor responsively to the wire being drawn becoming under abnormal tension.

5. Wire-drawing apparatus comprising, in combination, a wire-drawing machine, a plurality of wire-holding reels adapted to receive bundles of wire and to feed wire therefrom continuously to the wire-drawing machine, mechanism for feeding wire uninterruptedly from the reels to the wire-drawing machine, the mechanism including guide means normally freely passing the wire therethrough while stopping the wire responsively to contact of surface abnormalities on the wire of predetermined amount, a motor for operating the wire-drawing machine, a power circuit for supplying current to drive the motor, a control circuit for the motor, a relay normally closing the power circuit, and two switches either of which is adapted to close the control circuit for opening the relay responsively to abnormal conditions in the wire, thereby stopping the motor, one of the said switches being a limit switch adapted to be closed by the wire passing to the wire-drawing machine becoming subjected to predetermined abnormal tension incident to stopping the wire at the guide means, and the other of the said switches being closed responsively to release of tension on the wire incident to a breaking of the wire, existence of either of these abnormal conditions immediately stopping the wire-drawing machine.

6. Wire-drawing apparatus comprising, in combination, a wire-drawing machine, a plurality of wire-holding reels adapted to receive bundles of wire and to feed wire therefrom continuously to the wire-drawing machine, a planetary unwinding arm suitably mounted on each of the reels for receiving wire from the reels and adapted to rotate around the reels to unwind the wire responsively to pull exerted on the wire by the wire-drawing machine, a motor for operating the wire-drawing machine, a power circuit for driving the motor, a relay normally closing the power circuit, a control circuit for the motor adapted

when energized to open the relay to break the power circuit, feeding mechanism for supplying wire to the machine as the wire becomes unwound from the reels by the unwinding arms, the feeding mechanism comprising a support, a sleeve turnably mounted on the support, an extended arm on the sleeve adapted to move from one of the reels to another, depending upon from which of the reels the wire is being unwound, releasable

5 locking cam means for holding the sleeve and arm in adjusted position, the support being positioned intermediate the reels and the wire-drawing machine, a second sleeve slidably mounted on the support, a pulley sheave on the arm over which the wire from the reels passes, a second pulley sheave on the slideable sleeve under which the wire passes, a third pulley sheave on the turnable sleeve over which the wire passes, a fourth pulley sheave on the support under which the wire passes directly to the machine, a limit switch on the slideable sleeve adapted to close for energizing the control circuit to open the relay responsively to lifting of the slideable sleeve under abnormal tension on the wire, thereby instantaneously stopping the motor responsively to the wire becoming under such abnormal tension, and a second switch for the control circuit also adapted to open the relay to stop the motor instantaneously upon release of tension on the wire

30 responsive to a break occurring in the wire.

7. Wire-drawing apparatus comprising, in combination, a wire-drawing machine including a plurality of wire-holding instrumentalities adapted to receive bundles of wire for continuous feeding thereof to the wire-drawing machine, a source of power for the wire-drawing machine, a power circuit for operating the machine, wire distributing mechanism comprising planetary unwinding means mounted on each of the wire-

35 holding instrumentalities, a feeding arm associated with the wire-holding instrumentalities intermediate the said instrumentalities and wire-drawing machine, the planetary unwinding means and feeding arm being operable by tension imparted to the wire which is fed through the said means and arm, the said arm being shiftable from one to another of the wire-holding instrumentalities responsively to directional tension on the wire for unwinding wire continuously from

40 the bundles and supplying the wire continuously to the wire-drawing machine, and control instrumentalities for instantaneously stopping the machine responsively to an interruption of the wire supply to the machine, the said instrumentalities

45 including a control circuit, means in the control circuit for energizing the control circuit responsively to interruption of the wire supply, a normally closed control switch in the power circuit and mechanism in the control circuit for opening the control switch responsively to energizing the control circuit, thereby opening the power circuit and instantaneously stopping the wire-drawing machine.

8. Wire-drawing apparatus comprising, in combination, a wire-drawing machine including a plurality of wire-holding instrumentalities adapted to receive bundles of wire for continuous feeding thereof to the wire-drawing machine, a source of power for the wire-drawing machine, a power circuit for operating the machine, wire-distributing mechanism comprising planetary unwinding means mounted on each of the wire-holding instrumentalities, a feeding arm associated with the wire-holding instrumentalities intermediate the said instrumentalities and ma-

chine, the planetary unwinding means and feeding arm being operable by tension imparted to the wire which is fed through the said means and arm, the said arm being shiftable from one to another of the wire-holding instrumentalities responsive to directional tension on the wire for unwinding wire continuously from the bundles and supplying the wire continuously to the wire-drawing machine, means for detecting uneven-

ness in the wire such as kinks in the wire or lumps thereon as the wire is being supplied to the wire-drawing machine but before the said unevenness reaches the said machine, thereby causing interruption of the wire supply to the machine, and control instrumentalities for instantaneously stopping the machine responsive to an interruption of the wire supply to the machine.

DANIEL D. SYMMES.
